PORTABLE TABLE

Virgil James Hutchison, 8901 W. 97th St.,
Overland Park, Kans. 66212

Filed Oct. 6, 1972, Ser. No. 295,500

Term of patent 14 years

Int. Cl. D6—03

U.S. Cl. D6—178

Fig. 1.

Fig. 3.

Fig. 2.

Fig. 4.

Fig. 5.

Fig. 6.

Fig. 7.

FIG. 1 is a perspective view of a portable table embodying my design.

FIG. 2 is a front elevational view thereof.

FIG. 3 is a side elevational view thereof.

FIG. 4 is a top plan view thereof and showing a drawer in a partially open position.

FIG. 5 is a front elevational view thereof shown in a folded position.

FIG. 6 is a rear elevational view thereof also shown in a folded position.

FIG. 7 is a side elevational view thereof also shown in a folded position.

I claim:

The ornamental design for a portable table, as shown.
